SUCTION CLEANER

William H. Kitto, Canton, Ohio, assignor to The
Hoover Company, North Canton, Ohio, a cor-
poration of Ohio

Application May 5, 1933, Serial No. 669,489

6 Claims. (Cl. 15—8)

The present invention relates to suction cleaners in general, and more particularly to a new and novel agitator bearing-protective construction for use in a suction cleaner.

It is an object of the present invention to provide a new and improved suction cleaner agitator construction. A further object is the provision of a new and novel construction to prevent the collection of dirt and foreign matter in the agitator bearing. Still another object is the provision, in a suction cleaner, of an agitator construction which includes a supporting shaft, a rotatable body mounted upon the shaft, a bearing which rotatably supports the body upon the shaft, and means concentric with the bearing and the shaft to protect the said bearing from foreign matter. These and other more specific objects will appear upon reading the following specification and claims, and upon considering in connection therewith the attached drawing to which they relate.

In the drawing, in which a preferred embodiment of the present invention is disclosed:

Figure 1 is a front view of a modern suction cleaner with the nozzle partially broken away showing a rotary agitator embodied therein;

Figure 2 is an enlarged section of the end construction of the cleaner agitator;

Figure 3 is a side elevation of the agitator, partially in section, showing the bearing-protecting means constructed in accordance with the present invention; and

Figure 4 is an exploded view of the agitator end construction made in accordance with the present construction.

In the modern suction cleaner positive agitating means are provided to assist the cleaning air in its function of removing foreign matter from the surface covering undergoing cleaning. It has been determined that rotary agitators, comprising a large diameter body provided with rigid surface-contacting beating elements and flexible surface-contacting brushes, are the most satisfactory agitators. Such agitators are normally positioned within the cleaner nozzle in the path of the cleaning air which carries the foreign matter from the surface covering undergoing cleaning. In such position it is necessary to protect the agitator bearings from the passing foreign matter. In the agitator constructed in accordance with the present invention means have been provided which insure the long life of the bearings and their freedom from foreign matter.

Referring again to the drawing, and Figure 1 in particular, a modern suction cleaner is shown

which comprises a nozzle 1, encircled and protected by a resilient furniture guard 2, a motor casing 3 which houses an unshown driving motor arranged to drive the unshown suction-creating means of the cleaner, a pivoted handle 4, through which the operator may exert the propelling force necessary to operate the cleaner, and the usual supporting wheels 5, 5, etc. which make the machine readily movable. Within the nozzle 1 and extending transversely thereacross is a rotary agitator comprising a relatively large diameter cylindrical body 6 which is provided on its surface with helically extending surface contacting beater elements 7, 7, and which carries brushes 8, 8 which co-operate with the beater elements to remove the foreign matter from the surface covering. Substantially centrally of the body 6 is provided a pulley surface 9 of reduced diameter which as adapted to receive a driving belt from an unshown motor pulley. A through supporting shaft 10 extends across the nozzle 1 and is non-rotatably mounted in suitable supports at the nozzle side walls. The shaft rotatably supports body 6 by means of a ball bearing 11 at each of its ends, the outer race of each bearing seating within an end wall or cup 12 on the outer shoulder 13 of which an end of the cylindrical body seats. Each end wall or annulus 12 is shaped in a very definite manner, being formed with a peripheral flange 14, a circumferential channel 15, which, in the assembled relation, is divided into channels 16 and 17 by a permanently attached ring member 18. A seal 19 is carried by the end wall 12 which encircles the shaft 10 closely adjacent the bearing 11 and prevents the passage of dirt-laden air therethrough with the help of a seal 20 which is carried by the bearing itself upon its opposite side.

A member, commonly known as a thread-guard, indicated generally by the reference character 21, is manufactured of three pieces comprising a plate 22, provided with an outer flange 23, a channeled ring 24, the axially extending sides of which are indicated by the reference characters 25 and 26 and which are of such diameter that they are adapted to extend within the channels 16 and 17, and a nut member 27, which secures the thread-guard to the threaded end of the stationary shaft 10. For manufacturing purposes, it is found desirable to make the thread-guard 21 of the three elements described, but in actual use in a suction cleaner these elements are fixedly and permanently secured together, as by welding, and form a unitary construction, as do the end-cup 12 and the ring 18.

In the operative relationship the inner race of the bearing 11 seats upon the shouldered end of the shaft 10 and supports the channeled end cup 12. A spring washer 28 contacts the outer race 5 of the bearing 11 and the seal 19 and resiliently opposes axial movement of the outer bearing race relative to the inner. The bearing is retained on the shaft by the thread-guard 21 which seats in screw-threaded relationship thereon. With 10 the thread-guard in place its outer flange 23 overlies the radial flange 14 of the end cup while the flanges 25 and 26 extend within, but are spaced from the walls of, the channels 16 and 17, providing a labyrinth construction in which a 15 circuitous path is formed between the exterior of the agitator and the interior of the bearing 11. Viewed separately the individual flanges 14 and 23 cooperate to provide a narrow opening and to restrict the passage of foreign matter inwardly 20 toward the bearing 11. The flanges 25 and 26 cooperate with air channels 16 and 17 to provide a winding pathway which air or foreign matter must traverse in reaching the bearing. In co- 25 operation with this protection are the seals 19 and 20.

I claim:—

1. A suction cleaner agitator including a rotary body, a stationary supporting shaft, a bearing on said shaft, an end member supporting said body 30 on said bearing, concentric radially spaced channels in one side of said member, a stationary end plate carried by said shaft adjacent said end member and provided with concentric spaced flanges extended into said channels, and cooperating therewith to form a labyrinth to protect said bearing against the ingress of foreign matter.
2. A suction cleaner agitator including a rotary body, a stationary supporting shaft, a bearing on said shaft, an end member rotatably supporting 40 said body on said bearing, said member being provided with a radially extending flange on its periphery and spaced concentric axially extending channels, a stationary end plate seated on said shaft provided with an outer flange overlying said 45 radially extending flange and spaced concentric flanges extending in said channels, said flanges and channels cooperating to form a labyrinth to protect said bearing against the ingress of foreign matter.
3. A suction cleaner agitator including a body, 50

a stationary supporting shaft, a bearing on said shaft, an annulus of channel section with the sides of the channel parallel to the body axis seated on said bearing and rotatably supporting said body, a ring permanently secured in the channel in said annulus and forming two concentric channels, a stationary flanged plate adjacent said annulus with its flange extended there-over, a screw threaded nut permanently attached to said plate securing it to said shaft, a channelled 10 ring member permanently attached to said plate member with the sides of said channel extended into the spaced channels formed in said annulus, the walls of said ring cooperating with the spaced channels to form a labyrinth to protect said bearing against the ingress of foreign matter. 15

4. In a suction cleaner agitator, a cylindrical closed body, a shaft extended thru said body, a bearing seated on said shaft, means seated on said bearing and mounting said body thereon, said 20 means including radially spaced axially and outwardly directed circular walls, a guard member enclosing said shaft in substantially air tight relationship at the end of said body and immediately adjacent said means and including inwardly 25 directed circular walls, and means sealing said first means to said shaft adjacent said bearing.

5. In a suction cleaner agitator adapted to be positioned in a dirt-laden air stream, a cylindrical closed body, an end wall closing one end of said 30 body, said wall being formed with a bearing-receiving seat and radially spaced circular channels around said seat, a bearing in said seat, a shaft seated in said bearing, and a guard member carried by said shaft adjacent said end wall and 35 provided with circular radially spaced axially extending walls which extend into the channels formed in said end wall.

6. In a suction cleaner agitator adapted to be positioned in a dirt-laden air stream, a cylindrical closed body, an end wall closing one end of said body, a bearing carried by said wall, a shaft carried by said bearing, and a guard member mounted on said shaft in sealed relationship adjacent said end wall, said end wall and said 45 guard member being provided with cooperating channels and flanges positioned concentric relative to the axis of rotation and within the circumference of said closed body.
